UNITED STATES PATENT OFFICE

ROBERT G. ANDERSON, OF PLAINFIELD, NEW JERSEY, ASSIGNOR TO INTERNATIONAL MOTOR COMPANY, OF NEW YORK, N. Y., A CORPORATION OF DELAWARE

REMOVABLE PEDESTAL LINER

Application filed December 10, 1929. Serial No. 412,992.

The present invention relates to railway running gears and embodies, more specifically, an improved pedestal mounting by means of which the pedestal which bears the axle 5 of the truck is effectively mounted in the pedestal jaws of the truck frame.

In the mounting of pedestals upon the pedestal jaws of railway truck frames, considerable difficulty is frequently encountered 10 by reason of the fact that the sizes of the jaws vary, not only with varying designs but by reason of inaccuracies during the manufacture thereof. As a result, the complete interchangeability of parts is seriously decreased, the pedestals for a given journal box 15 being susceptible of use in connection with only a limited number of truck frames and pedestal jaws carried thereby. Where pedestal liners are used to overcome the foregoing 20 irregularities in designs, considerable difficulty has been experienced in removing or replacing liners without taking down the entire pedestal structure.

A further disadvantage of existing structures is that pedestal liners heretofore made 25 have been of such character that they cannot be removed or replaced without dropping the entire journal box in order that the liners may be removed from the pedestal jaws. The normal construction involving the use of 30 pedestal liners is such that the liners overlie a horizontal flange, or flanges, formed at the base of each pedestal jaw. These flanges extend outwardly into substantially the plane 35 of the liner and thus prevent its being dropped out for inspection and replacement.

An object of the present invention, therefore, is to provide a pedestal liner construction of such character as to facilitate its application to pedestal jaws of varying sizes.

A further object of the present invention is to provide a pedestal liner which may be applied to pedestal jaws of varying sizes, the installation and removal thereof being 45 facilitated by reason of the improved structure to be described hereinafter.

A further object of the invention is to provide a pedestal liner which may be readily applied without removing the journal box or 50 lifting the pedestal jaws, such application

including the spot welding of the liner to the respective jaws.

Further objects, not specifically enumerated above, will be apparent as the invention is described in greater detail in connection with the accompanying drawings, 55 wherein:

Figure 1 is a view in side elevation, showing a pedestal jaw and liners therefor constructed in accordance with the present invention. 60

Figure 2 is a view in section, taken on line 2—2 of Figure 1, and looking in the direction of the arrows.

Figure 3 is a perspective view showing a 65 pedestal liner in greater detail.

Referring to the above drawings, *a* designates a pedestal jaw having jaw members *a'* and *a''*. The jaw may be secured to the truck frame by means of bolts extending through 70 bolt holes *a*³ in the usual manner.

At the base of each jaw member *a'* and *a''*, horizontal flanges *a*⁴ are formed, such flanges normally extending toward the pedestal jaw and terminating adjacent a wear plate *a*⁵, 75 shown in dotted lines in Figure 1.

In order to adjust the distance between the wear plates *a*⁵ in accordance with the foregoing conditions, liners *b* are provided, such liners being secured to the respective jaws by 80 spot welding as indicated at *b'*. The liners are preferably formed with longitudinal grooves *b*² for engaging the wear plates *a*⁵ and receiving the same telescopically. At the bottom of the grooves, rounded stop members *b*³ 85 are formed, these stop members limiting the upward movement of the liners and thus properly positioning them when they are slid upwardly into position. When the stop members *b*³ have engaged the lower extremities 90 of the wear plates *a*⁵, the liner is welded to the respective jaws as indicated at *b'*, thus readily effecting the mounting of the liners.

It will be seen that the liners may be applied by sliding them upwardly along the proper faces of the pedestal jaws, there being no obstruction to such movement. In this manner, it will not be necessary to lift the pedestal jaws from the pedestal and journal box in order that the liners may clear the 95 100

horizontal flanges α^4 as has been necessary in existing designs. To remove the liners, it is only necessary to break the weld, the liners thus being dropped from assembled position without removing the journal box from the pedestal. In the same manner, a new liner may be slid up in place and welded without the necessity of dropping the journal box from the pedestal. It will further be seen that the liners may be wedged from behind to compensate for wear of the journal boxes.

While the invention has been described with specific reference to the accompanying drawings, it is not to be limited, save as defined in the appended claim.

15 I claim as my invention :

A pedestal construction for railway trucks comprising spaced pedestal jaws, plates projecting beyond the opposed faces of the jaws, 20 U-shaped liners, stops on the liners at one end thereof and extending between and lying flush with the sides thereof, and means to secure the liners to the jaws over the plates, the stops abutting the lower ends of the plates.

25 This specification signed this 3d day of December, A. D. 1929.

ROBERT G. ANDERSON.
